UNITED STATES PATENT OFFICE

JOSEPH G. TURRIN, OF NEW PHILADELPHIA, OHIO

AUTOMATIC AIR AND STEAM COUPLER

Application filed September 24, 1928. Serial No. 308,075.

This invention relates to car couplers and its general object is to provide a coupler for the air and steam lines of cars, that couples automatically and simultaneously with the 5 operation of the usual coupling now generally employed for coupling the cars themselves together, and the steam and air couplings are uncoupled accordingly with the uncoupling of the car couplings, therefore 10 an attendant does not have to endanger himself by stepping between the cars for this purpose.

A further object of the invention is to provide a coupling for the steam and air pipes 15 of cars, that is capable of forming a leak proof connection between the point of junction of the air lines.

Another object of the invention is to provide a coupling device of the character set 20 forth, that is simple in construction, inexpensive to manufacture and install and efficient in operation and service.

This invention also consists in certain other features of construction and in the 25 combination and arrangement of the several parts, to be hereinafter fully described, illustrated in the accompanying drawings and specifically pointed out in the appended claim.

In describing my invention in detail, reference will be had to the accompanying 30 drawings wherein like characters denote like or corresponding parts throughout the several views, and in which:

Figure 1 is a side elevation illustrating 35 my coupling device applied to the confronting ends of cars and showing the association thereof with the usual car coupling, with the parts in normal position.

Figure 2 is a similar view with the parts 40 in operative or coupled position.

Figure 3 is a top plan view of my coupling device in uncoupled position.

Figure 4 is a similar view in coupled position.

Figure 5 is a vertical sectional view taken

through the coupling in operative position.

Figure 6 is a face view of one of my coupling devices.

Figure 7 is a sectional view taken approximately on line 7—7 of Figure 1.

Referring to the drawings in detail, the letters A and B indicate the confronting ends of a pair of cars which are provided with the usual coupling members C for coupling the cars themselves together. These 50 coupling members are retained in position through the instrumentality of a pin as shown, and this pin is operated by a hand operating member D having one end connected with the pin, while its opposite end terminates in a handle E extending laterally 55 of the cars as shown. The hand operated member is formed with a horizontal portion F journaled at its ends to the car. This horizontal portion F has fixed thereto a weighted 60 lever G so as to normally retain the pin in 65 operative position.

Mounted for slidable movement in suitable cross members secured to the car are draw bars 1 having collars 2 secured thereto 70 for the purpose of acting as a stop for one of the ends of coil springs 3 while the opposite ends of said springs are disposed in contacting engagement with one of the cross members as best shown in Figure 2. By this 75 construction, it will be apparent that the draw bars are normally retained in their outermost position through the medium of the coil springs so that the draw bars are under 80 constant tension.

The outer ends of the draw bars terminate in forks 4 which pivotally receive the shanks 5 of heads 6. The heads are mounted for movement in a horizontal plane and to limit this movement there is provided leaf springs 8 having one of their ends fixed upon opposite sides of the forks while the opposite or free ends are disposed in contacting engagement with the opposite sides of the heads. The heads 6 are formed with re- 90

cesses 9 arranged in the underside thereof and extending through the front sides. Pivotally secured in each of the recesses 9 is an arm 10 of each coupling member and these arms have formed midway their ends apertured ears to receive one of the ends of a coil spring 11 while the opposite ends of these springs 11 are secured in recesses arranged in the heads and opening into the recesses 9 as clearly shown in Figure 5.

10 Formed with the outer ends of the arms 10 are the self coupling shoes of my device and these shoes are formed in a manner to cooperate with each other as shown in Figure 5.

15 The shoes each include spaced parallel members 12 and 13 which terminate in rounded outer ends having secured therein a pin 14 traversing the members for a purpose which will be presently apparent. Formed with the member 12 which is relatively narrower than the member 13 is a jaw 15 disposed in spaced relation with respect to the member 13 and has formed therein a bore 16 having its upper end extending at right angles so as to discharge on the inner side of the jaw 15. The discharge end of the bore has arranged therein a rubber gasket 17 having annular flanges providing a channel for the purpose of receiving the annular edges of the bore which is flanged for that purpose which is clearly shown in Figure 7 of the drawings. The lower end of the bore 16 extends through the bottom of the jaw which is provided with a collar 18 having fixedly secured thereto the adjacent end of the pipe line 19.

20 The jaw 15 of one shoe is disposed on one side thereof, while the jaw of the other shoe is disposed on the other, and the shoes of each jaw are similar in construction and have formed on their outer ends hooks 20 to be received by the pins 14 when the shoes are arranged in cooperative association as shown in Figure 5.

25 When in such cooperation, the inner sides of the jaws are disposed in contacting engagement with the rubber gaskets of the bores thereof disposed accordingly so as to provide a leak proof connection between the pipe lines 19 and 21.

30 The pipe lines 19 and 21 are provided for conveying steam and the pipe lines 22 and 23 convey air. The pipe lines 22 and 23 are likewise disposed in communication through the medium of my coupling and for this purpose the shoes are provided with substantially L-shaped members 24 having bores 25 formed therein with the pipes 22 and 23 in communication therewith. The inner ends of the bores are disposed laterally to the inner side of the L-shape members 24 which are provided with recesses 26 to receive the rounded heads of said members 24 as shown when the shoes are in cooperative 35 position. The confronting ends of the bores

are flanged to accommodate rubber gaskets 27 of the same character as clearly shown in Figure 7, so as to provide a leak proof connection when the gaskets 27 are disposed in contacting engagement as shown in Figure 5.

70 In order to secure the shoes in cooperative position as shown in Figure 5, I provide means for coupling the heads together and securing them accordingly and this means includes the housing member 28 on each head and these housing members are formed with horizontal walls having pivotally secured therebetween jaws 29 arranged for movement in a horizontal plane. The jaws 29 are enlarged as at 30 at one end to provide a counter-balancing means therefor, while the opposite ends terminate in hook members 31 having formed therein hook shaped recesses 32 of a size to accommodate the large portions of the hook member as shown, Figure 80 4, as the recesses receive the large portions when the coupling is disposed in operative position in the manner as shown in Figure 4.

85 The pivot pins of the jaws 29 pass through the large portions of the hook members and spaced parallel ears 33 arranged in cooperating pairs as best shown in Figure 3. By this construction, it will be apparent that when the jaws 29 come together that the large portions of the hook members will be guided into the hook shaped recesses 32 by the small portions of the hook members due to the engagement of the large portions of the hook members of each of the jaws with the small hook portions of the 95 members.

90 The jaws 29 are held in cooperative association through the medium of a latching means and each of these latching means include a lever 34 terminating at one end in an eye 35 secured to the head by a pin for pivotal movement thereon as will be apparent. The opposite end of the lever 34 is directed upwardly at an inclination as at 36 and terminates in an end bent at right angles to the upwardly disposed portion as best shown in Figure 2. The latching means also includes a substantially right angle shaped lever 37 having one of its ends secured to the eye 35 while its opposite end terminates in an eye 36' for the purpose of accommodating one of the end links of a chain 39 which is secured thereto and the other end of the chain is fixed in an eye 40 of a link 41 which is secured to the weight 105 of the weighted lever G. The latching means of each of the heads is provided with a coil spring 42 for urging the right angle bent ends 43 of the levers 34 in a downward direction so that these ends of the levers 34 may retain the jaws 29 in either an operative or inoperative position as shown in Figures 2 and 1 respectively.

110 In other words, when the jaws 29 are disposed in inoperative position, the right angle 130

bent ends of the levers 34 normally rest upon the top of the enlarged portion 30 of the jaws but when the jaws are disposed in operative position as shown in Figure 2, the right angle bent ends engage the rear sides of the jaws so as to prevent them from becoming separated as will be apparent.

From the above description and disclosure of the drawings, it will be obvious that I have provided a coupling that automatically secures the steam and air lines of cars together in a leak-proof manner, and the coupling members accomplishing this purpose are operated to coupling position when the cars come together and are uncoupled simultaneously with the uncoupling of the car coupling means.

The outer edges of the confronting sides of the jaws 15 are slightly beveled as at 44 as shown in Figure 3 so as to insure proper cooperation between the jaws when the latter come together. The shoes are provided with recesses 45 disposed between the jaws 15 and the members 13, and these recesses 45 have rounded inner walls which cooperate with the rounded upper sides of the jaws 15 to cause the jaws to be moved downwardly when the shoes come together so as to fix the hooks 20 of the jaws 15 about the pins 14. The jaws 15 are not movable by themselves but the shoes in their entireties move on the pivots of the arms 10 as will be apparent upon inspection of Figure 5.

It is thought from the foregoing description that the advantages and novel features of my invention will be readily apparent.

I desire it to be understood that I may make changes in the construction and in the combination and arrangement of the several parts, provided that such changes fall within the scope of the appended claim.

What I claim is:

In combination with a coupling for rail-way cars, a combined steam and air coupling comprising spring pressed draw bars, spring pressed heads pivotally secured to said draw bars and having recesses formed therein, means for retarding the pivotal movement of said heads, arms pivotally secured in said recesses, ears formed with said arms, shoes formed with the free ends of said arms, coil springs secured to the ears and heads for urging the shoes together, jaws formed with said shoes and having rounded upper surfaces engageable with rounded walls of recesses formed in said shoes, spaced members included in each shoe with the jaws between the same, pins carried by said shoes and traversing one member and its jaw, hooks formed with said jaw and being adapted to be received by said pins for securing the shoes together, L-shaped members formed with said shoes and together with said jaws being provided with

bores, said L-shaped members and jaws co-operating for disposing the bores thereof in communication to provide a leak proof connection therebetween, air and steam pipe lines in communication with said bores, rounded heads formed with said L-shaped members which are recessed to accommodate the heads of each other, means for coupling the first mentioned heads together, latching means for said coupling means and being operable upon operation of the car coupling.

In testimony whereof I affix my signature.

JOSEPH G. TURRIN.
